VEHICLE DOOR RECEPTACLE

Lionel J. Theberge, 225 S. Main St., Rochester, N.H.
Filed Jan. 31, 1961, Ser. No. 86,031

2 Claims. (Cl. 296—37)

This invention relates to a novel receptacle for hollow doors.

The primary object of the invention is the provision of a more practical and efficient door receptacle which opens to the free edge of the door, so as to be readily accessible when the door is in open position, and so as to be protectively closed, when the door is in closed position, by the fame in which the door is hung.

Another object of the invention is the provision of a door receptacle of the character indicated above, whose installation desirably eschews mutilation and weakening of the inner of the door panel, and which involves a minimum of cutting of the edge panel of the door.

A further object of the invention is the provision of a vehicle door receptacle of the character indicated above, such as a receptacle for an umbrella, which comprises a removable tube inserted through an opening formed in the edge wall of the door and having spring catch means, engaged with the edge wall, for holding the tube in place.

A still further object of the invention is the provision of a simple and inexpensive vehicle door assembly of the character indicated above, which is composed of a minimal number of simple and easily manufactured parts, and which is quickly and easily installable in a hollow door.

Other important objects and advantageous features of the invention will be apparent from the following description and the accompanying drawings, wherein, for purposes of illustration only, a specific form of the invention is set forth in detail.

In the drawings:

FIGURE 1 is a perspective view of a vehicle door showing a receptacle installed therein in accordance with the present invention, and containing an umbrella;

FIGURE 2 is a perspective view of the receptacle, per se;

FIGURE 3 is an enlarged fragmentary vertical longitudinal section taken on the line 3—3 of FIGURE 1; and,

FIGURE 4 is a fragmentary vertical transverse section taken on the line 4—4 of FIGURE 3.

Referring in detail to the drawings, wherein like numerals designate like parts throughout the several views, a motor vehicle door, generally designated 10, is shown, which is hinged in a motor vehicle body door frame (not shown). The door 10 has an outer side panel 11, an inner side panel 12, and a vertical free edge wall 14, which, when the door 10 is in closed position, faces and substantially abuts the free edge wall 12. It will be understood, however, that the present invention is equally applicable to any forms of hollow doors having free end walls. The free edge wall 14 is, in accordance with the present invention, provided, at a suitable location above the bottom wall 15, of the door 10, with a circular opening 16, through which a receptacle 18 is inserted.

The receptacle 18, which, by way of illustration, is shaped to conformably contain a folded umbrella 20, is of elongated tubular form and is tapered from its outer end 22 to its inner end 24, the receptacle being somewhat longer than the umbrella 20, so as to provide for the accommodation of umbrellas of different lengths and girths having straight handles 26. The receptacle 18 is preferably made of plastic material.

On the outer end of the receptacle 18 an annular lateral flange 28 is formed, which abuts the outer surface of the door edge wall 14, around the opening 16, the receptacle, at its outer end, being a relatively close fit in the opening 16.

2

The catches 30 are preferably in the form of flat arms 32, fixed to and extending inwardly from the flange 28 and spaced outwardly from the sidewall of the receptacle 18, the arms 32 terminating, at their inner ends in laterally outwardly extending longitudinally outwardly bowed cam terminals 34. The cam terminals 34 serve to cam the catches toward the receptacle sidewall 36, as the receptacle is pushed home through the opening 16, so that the arm terminals can pass through the opening, and spring out behind and retainably engage the inner surface of the door edge wall 14. The cam terminals also serve, upon exertion of an outward pull on the receptacle 18, to cam the cam terminals inwardly toward the receptacle, so as to enable the receptacle to be removed through the opening 16.

The receptacle sidewall 36 is provided, in its underside, with longitudinally spaced drain openings 38, whereby water from a wet umbrella stored in the receptacle 18 can drain from the receptacle and promote drying of the umbrella.

The general conformance in taper of the receptacle 18 to the taper of a folded umbrella, and the fact that insertion of a folded umbrella in the receptacle obtains a slight jam fit of the umbrella therein, assures against rattling and shifting of the umbrella in the receptacle.

Although there has been shown and described herein a preferred form of the invention, it is to be understood that the invention is not necessarily confined thereto, and that any change or changes in the structure of and in the relative arrangements of components thereof are contemplated as being within the scope of the invention as defined by the claims appended hereto.

What is claimed is:

1. In combination, a vehicle door having outer and inner side panels, a bottom wall, and a vertical free edge wall, said edge wall being formed with an opening spaced above said bottom wall, a tubular receptacle having a sidewall and outer and inner ends, said receptacle being inserted endwise through said opening and having a lateral flange on its outer end, said flange being engaged with the outer surface of the edge wall around said opening, and means removably securing the receptacle in place, comprising a plurality of circumferentially spaced spring catches fixed to and extending inwardly from said flange and extending through the opening and engaged behind the edge panel.

2. In combination, a vehicle door having outer and inner side panels, a bottom wall, and a vertical free edge wall, said edge wall being formed with an opening spaced above said bottom wall, a tubular receptacle having a sidewall and outer and inner ends, said receptacle being inserted endwise through said opening and having a lateral flange on its outer end, said flange being engaged with the outer surface of the edge wall around said opening, and means removably securing the receptacle in place, comprising a plurality of circumferentially spaced spring catches fixed to and extending inwardly from said flange and extending through the opening and engaged behind the edge panel, said catches comprising arms engaged with the edge of the opening, said arms terminating at their inner ends in longitudinally and outwardly bowed cam terminals engaged with the inner surface of the edge wall.
